[57] CLAIM

The ornamental design for a medical monitoring equipment probe connector for pulse oximeters.

DESCRIPTION

FIG. 1 is a perspective view of the medical monitoring equipment probe connector for pulse oximeters of the present invention;

FIG. 2 is a top view of the probe connector of FIG. 1; FIG. 3 is a bottom view of the probe connector of FIG. 1;

FIG. 4 is an end view of the probe connector of FIG. 1; FIG. 5 is a cable end view of the probe connector of FIG. 1;

FIG. 6 is a left side of the probe connector of FIG. 1; and,

FIG. 7 is a right side view of the probe connector of FIG. 1.

The broken line showing of the tube is for illustrative purposes only and forms no part of the claimed design.

FIG. 1

FIG. 2
